(57) **CLAIM**

The ornamental design for a “server rack cover,” as shown and described.

DESCRIPTION

FIG. 1 is a front view of a server rack cover according to a first embodiment.

FIG. 2 is a top view of the server rack cover according to a first embodiment.

FIG. 3 is a bottom view of the server rack cover according to a first embodiment.

FIG. 4 is a side view of the server rack cover from a right side according to a first embodiment.

FIG. 5 is a side view of the server rack cover from a left side according to a first embodiment.

FIG. 6 is an isometric view of the server rack cover from the right side according to a first embodiment; and,

FIG. 7 is an isometric view of the server rack cover from the left side according to a first embodiment.

The features shown in broken lines illustrate portions of the storage device and form no part of the claimed design.
